UNITED STATES PATENT OFFICE.

JOHN STOGDELL STOKES, OF MOORESTOWN, NEW JERSEY, ASSIGNEE TO STOKES & SMITH COMPANY, OF PHILADELPHIA, PENNSYLVANIA, A CORPORATION OF PENNSYLVANIA.

AIR OR MOISTURE PROOF PACKAGE.

1,343,235.

Specification of Letters Patent. Patented June 15, 1920.

Application filed February 25, 1918. Serial No. 219,008.

To all whom it may concern:

Be it known that I, JOHN STOGDELL STOKES, a citizen of the United States, residing at Moorestown, in the county of Burlington and State of New Jersey, have invented new and useful Improvements in Air or Moisture Proof Packages, of which the following is a specification.

This invention relates to air or moisture-proof packages, and more especially to packages of the sealed wrapped type wherein the wrapper is adhesively secured to exterior faces of the commodity container.

The enveloping of the commodity container by a suitable wrapping blank with the blank folded about the container and adhesively secured to exterior faces of the container, is one of the developments in packaging operations of recent years, the general arrangement being such as to permit the blank to be applied by automatic or semi-automatic machines. This ability to complete the packaging by mechanical manipulation not only provides for comparatively high capacity output, but in addition enables the package wrapping to be uniform so as to provide packages of uniform appearance. Packages of this type are generally air proof and, to some extent, moisture-proof, through the fact that the adhesive by which the blank is secured to the container is generally applied throughout the surface extent of the securing face of the blank, thus providing a coating which tends to prevent access of moisture to the container and its contents.

As will be understood, however, packages of this type may be subjected to conditions such as may affect this coating connection between the wrapper and the container intermediate the time of wrapping and the time when the container is finally opened, and thereby tend to reduce the air and moisture-proof qualities of the package. And where packages are subjected to such conditions, the desired protection of the contents of the package may be affected.

The present invention is designed more particularly to meet these conditions, this result being had by generally protecting this coating against the effect of these conditions, by interposing between the coated face of the wrapper blank and the exterior of the package a layer which is substantially air and moisture-proof in character, a suitable

material for such layer being, for instance, paraffin. And since the exterior face of the package is generally printed in the form of a label, this layer is preferably interposed between the opposite faces of the blank.

In order that this idea may be employed commercially, certain difficulties must be overcome. For instance, the cost of production of the package should not be materially increased, it being understood that packages of the sealed wrapped type generally are well established in the trade and marketed in large quantities, being practically standard as to package and price; hence, a package which would materially affect the cost and selling price of the package is a disadvantage commercially. Another factor is the practical necessity of providing the wrapping operations by automatic machines in order that the wrapping cost may be reduced to the minimum and the desired uniformity be obtained. In this latter connection, it will be understood that one of the factors of successful operation under high capacity conditions is the character of the blank, it being more or less essential that it be flexible and pliable and readily folded, in order that the folding operations may be properly performed in the machine. In addition, it is desirable, both by reason of the package formation and of the machine operation, that the wrapper be comparatively light in weight.

Wrapper applying of this type under automatic operation practically necessitates that the adhesive coating be applied to the wrapper blank in advance of wrapper application, and therefore the face on which the adhesive coating is placed must be of a character which will carry such adhesive coating and which will permit of affixing to the container by the action of the adhesive coating. While the blanks now generally employed provide this result by reason of the character of the blank, a radical change in condition is present where the attempt is made to operate in connection with a blank having a layer of the type referred to. Where this protecting layer of paraffin is applied to a wrapper secured in position on the container—as by dipping the wrapped package after the adhesive coating had dried—this difficulty is not present, since the adhesive has become set and is therefore unaffected by the presence of the par-

affin; such operation, however, is practically useless commercially both by reason of cost of operation and low capacity operations, in addition to which the paraffin coating would be external of the package and therefore readily damaged. Nor would these disadvantages be materially eliminated by adding to the dipped package an additional wrapping element so as to protect the paraffin coating, since this would simply increase the general cost of operation and affect the capacity. Hence, it is practically essential that the wrapper blanks be completed as to the paraffin layer, prior to wrapping application, and since the adhesive is necessarily more or less fluid during the latter operation, this paraffin layer must be provided in advance of the application of the adhesive coating.

20 The difficulty of applying adhesive to a paraffin sheet is well known, the repellent action of the paraffin tending to reduce the absorption of the adhesive by the sheet, and this fact provides one of the difficulties 25 which must be overcome before successful production of packages of this type having this protecting feature, can be provided under commercial conditions.

In the present invention I meet these difficulties by the use of a composite sheet for the blank, this sheet being of ply formation—generally two plies of paper—the plies being united by the paraffin layer, the latter being comparatively thin. The paper plies 35 are preferably of comparatively thin stock and are preferably of calendered paper—tissue paper or the commercial product known as "glacine" paper may be employed. The paraffin is located between the plies and 40 unites the confronting faces thereof, and may be applied either to the face of one ply or to the face of both plies, the uniting of the plies being by suitable means such as heat and pressure, the layer being somewhat 45 in the nature of a film. By the use of the calendered paper, the paraffin is kept from permeating through the ply and hence the outer face of the ply is not affected by the presence of this paraffin and is therefore 50 capable of receiving the adhesive coating and providing the securing action between the blank and the container. The opposite outer face of the sheet is similarly free from the effects of the paraffin and is therefore 55 capable of being printed upon if desired, or, where it is desired to provide an additional wrapping, this face is capable of providing the proper securing action of the adhesive by which the additional wrapper is secured in 60 position.

To these and other ends, therefore, the nature of which will be readily understood as the invention is hereinafter disclosed, said invention consists in the improved construction and combination of parts herein-

after fully described, illustrated in the accompanying drawings, and more particularly pointed out in the appended claims.

In the accompanying drawings, in which similar reference characters indicate similar parts in each of the views:

Figure 1 is a perspective view showing one form of blank which may be employed and indicating diagrammatically a container about to be placed thereon.

Fig. 2 is a perspective view of the completed package.

Fig. 3 is a detail sectional view taken on a cross-section of a wrapped package and showing more particularly the general characteristic formation of the blank.

Fig. 4 is a similar view showing the use of an additional wrapper.

The blank shown in Fig. 1 is more or less illustrative, it being understood that the particular configuration of the blank may be varied as desired and to meet the particular character of wrapping operation to be had. For instance, the blanks may be of the types shown in U. S. Patents Nos. 1,219,788, 1,249,498, 1,249,548, 1,249,571, 1,249,607, or 1,253,436, these various types of blank contours being employed in connection with wrapping operations of different kinds, all, however, being designed to provide a sealed wrapped package and be applied by automatic or semi-automatic machines. The blank is indicated at B, the container being indicated at C, the latter being assumed to contain the commodity and as ready for wrapping operation, these patents indicating the general way in which the blanks are applied, wrapping of the container being designed to produce a tight or sealed wrapped package, viz: a package wherein the wrapper is adhesively secured to exterior faces of the container as distinguished from packages in which the wrapper is loose—free from adhesive connection to the container walls. As disclosed in these several patents, a face of the blank is coated with the adhesive, this coating extending substantially throughout the surface of such face. The coating is indicated conventionally at b.

As shown in Fig. 3, the blank is formed from a composite sheet, this sheet, in the instance illustrated, being of two-ply formation, each ply being of calendered paper and comparatively thin. The two plies, indicated at 10 and 11, being united by the interposed layer or film of paraffin—indicated at 12—the paraffin being applied in suitable manner, the plies being united as by the application of heat and pressure to the formation.

The sheet thus formed, although composite in character, is comparatively thin and light in weight, and has the characteristics of pliability and flexibility so as to 1

permit of ready folding during the wrapping operation. In addition, the outer faces of the sheet are not affected by the presence of the paraffin layer or film, so that such 5 faces are capable of receiving an adhesive coating or be printed upon as desired. If desired, the plies may be formed of glacine paper; or of highly-calendered paper. In either instance, the paraffin layer or film 10 does not sufficiently penetrate the plies as to affect the outer faces of such plies, the uniting action being sufficient for this particular use, due to the fact that in preparing the wrapping operation, both plies 15 take of the various folds employed and hence are not subjected to strains which would tend to separate the plies. And since the outer faces of the plies are not affected by the presence of the paraffin layer or film, 20 these faces can be given the treatment necessary in preparing the wrapper blank for the wrapping application.

In Fig. 4 I have shown the application of an additional wrapper to this composite 25 sheet wrapper, this outer wrapper being indicated at 14, the outer wrapper being adhesively connected to the wrapped package. Since the wrapper of the package is, for reasons above pointed out, of a type adapted 30 to permit of proper adhesive connection, this additional wrapper can be readily secured in position. This additional wrapper is not essential, being of advantage mainly where the package is intended for exporting 35 to tropical countries, in which case the additional adhesive coating which envelops the paraffin layer or film of the composite sheet, tends to decrease the possibility of affecting the air and moisture-proof character 40 provided by the wrapping. It is to be understood, of course, that this additional wrapper may or may not be employed as may be found desirable.

As will be understood, the blank formed 45 from the composite sheet, while providing the particular characteristics desired for maintaining air and moisture-proof conditions, is of a character which will permit its use as a blank usable with automatic or 50 semi-automatic machines such as are in commercial use at the present time, thus avoiding any necessity and expense of producing machines especially adapted for this purpose, thus providing no material increase 55 in the cost of packaging over that heretofore involved, while at the same time the high capacity operation may be had. In addition, the blank is of a type which provides the protective feature of the paraffin 60 layer or film without affecting the outer surfaces of the sheet in such manner as would prevent the use of the sheet as a blank in such machines.

While I have herein shown and described 65 several embodiments of the invention, and

ways in which it may be carried into effect, it will be understood that variations and modifications therein may be found desirable or necessary in meeting the exigencies of commercial use or application, and I desire to be understood as reserving the right to make any and all such changes or modifications as may be found desirable or essential, insofar as the same may fall within the spirit and scope of the invention as expressed in accompanying claims. 70 75

While I have herein referred to the material for uniting the plies as of a paraffin nature, it will be understood, of course, that this is more or less illustrative, it being 80 obvious that this layer may be of any material which can be applied to the material of the plies and which is adapted to act as a repellent against air or moisture and having adhesive properties. 85

What I claim is:

1. An air or moisture-proof package of the sealed wrapped type comprising a commodity container, and a wrapper enveloping the container and adhesively secured 90 to exterior faces thereof, said wrapper being of pliable readily-foldable paper of ply formation, said plies being united by a paraffin layer, said ply formation including a ply having an outer face impermeable to the 95 paraffin and capable of carrying an adhesive coating, whereby wrapping may be provided with an adhesively coated blank, the construction being such that the wrapper constitutes a complete seal for the package excluding air and moisture. 100

2. An air or moisture-proof package of the sealed wrapped type comprising a commodity container, and a wrapper enveloping the container and adhesively secured to 105 exterior faces thereof, said wrapper being of pliable readily-foldable paper of ply formation, said plies being united by a paraffin layer, the ply formation including a 110 ply of calendered paper to provide an exposed face of the blank capable of carrying an adhesive coating, whereby wrapping may be provided with an adhesively coated blank, the construction being such that the wrapper constitutes a complete seal for the 115 package excluding air and moisture.

3. An air or moisture-proof package of the sealed wrapped type comprising a commodity container, and a wrapper enveloping the container and adhesively secured to 120 exterior faces thereof, said wrapper being of pliable readily-foldable paper of ply formation, said plies being united by a paraffin layer and having faces impermeable to the paraffin and capable of carrying an 125 adhesive coating, whereby wrapping may be provided with an adhesively-coated blank, the construction being such that the wrapper constitutes a complete seal for the package excluding air and moisture. 130

1,343,936

4

4. An air or moisture-proof package of the sealed wrapped type comprising a commodity container, and a wrapper enveloping the container and adhesively secured to exterior faces thereof, said wrapper being of pliable readily-foldable paper of ply formation, said plies being united by a paraffin layer and having faces impermeable to the paraffin and capable of carrying an ad-

hesive coating, and an outer wrapper blank 10 adhesively connected to the applied blank, the construction being such that the wrapper constitutes a complete seal for the package excluding air and moisture.

In testimony whereof I have hereunto set 15 my hand.

JOHN STOGDELL STOKES.
